FLOODLIGHT

George B. Pauli, Chittenango, N.Y., assignor to Crouse-Hinds Company, Syracuse, N.Y., a corporation of New York

Filed Feb. 9, 1965, Ser. No. 83,745

Term of patent 3½ years

(Cl. D48—20)

FIG. 1

FIG. 2

FIG. 3

FIGURE 1 is a front elevational view of a floodlight showing my new design.

FIGURE 2 is a side elevational view of the floodlight shown in FIGURE 1.

FIGURE 3 is a bottom plan view of the floodlight shown in FIGURES 1 and 2.

The side of the floodlight opposite to that shown in FIGURE 2 is identical with that shown in FIGURE 1.

I claim:

The ornamental design for floodlight, as shown and described.
